RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING SYSTEM.

1,418,663.

Specification of Letters Patent.

Patented June 6, 1922.

Continuation of application Serial No. 384,829, filed May 28, 1920. This application filed November 19, 1920. Serial No. 425,152.

To all whom it may concern:

Be it known that I, RONALD A. McCANN, a citizen of the United States, residing at Swissvale, in the county of Allegheny and 5 State of Pennsylvania, have invented certain new and useful Improvements in Railway-Traffic-Controlling Systems, of which the following is a specification.

My invention relates to railway traffic controlling systems, and particularly to systems of the type comprising trackway devices located at intervals and each arranged to co-operate with train carried traffic governing apparatus to give a proceed or a 10 stop indication aboard the train according 15 as the device is energized or de-energized.

One object of my invention is the provision of trackway apparatus for systems of this character suitable for use on a single 20 track railway over which traffic moves in both directions.

The present application is a continuation 25 of my co-pending application filed May 28, 1920, Serial No. 384,829 for railway traffic controlling systems, in so far as the subject matter common to the two is concerned.

I will describe one form of trackway apparatus embodying my invention, and will then point out the novel features thereof in 30 claims.

In the accompanying drawings, Figs. 1, 2, and 3 are diagrammatic views showing one form of trackway apparatus embodying my invention, it being understood that a complete unit and part of another unit of a 35 traffic controlling system are formed by placing these views together end to end in the order named. Fig. 4 is a view showing in front elevation one form of trackway device illustrated diagrammatically in Figs. 1 to 4.

Similar reference characters refer to similar parts in each of the several views.

Referring now to Figs. 1 to 3, inclusive, 45 the reference characters 2 and 2^a designate the track rails of a single track railway C over which traffic moves in both directions, the portion of track here shown including two passing sidings A and B. The track 50 rails are divided by insulated joints 3 into a plurality of track sections 4-5, 5-6, * * * 18-19, and each section is pro-

vided with a track circuit comprising a track battery b, the rails of the section and a track relay designated by the reference 55 character T with an exponent.

Located adjacent the western end of the block between the sidings A and B is a signal S¹, which governs eastbound traffic into this block, and located adjacent the eastern 60

end of this block is a signal S², which governs westbound traffic into the same block. The block A-B is further provided with two intermediate signals S³ and S⁴ governing 65

eastbound and westbound traffic, respectively, through this block. As here shown, signals S³ and S⁴ are located at different points, the signal S³ being between signal 70

S¹ and S². Eastbound traffic through the passing siding B and along the track to the 75 east of this siding is governed by a signal S⁵, comprising a home arm H and a distant arm D. Westbound traffic through the passing

siding A and along the track to the west of this siding is governed by a similar signal 75 S⁶ located at the western end of the block A-B. Located in the rear of the signal S⁵ is a distant signal S¹¹, and located in the rear of signal S⁶ is a distant signal S¹². The portion 80

of track to the east of the passing siding B is provided with signals S⁷, S⁸, S⁹, S¹⁴ and S¹⁰, which signals correspond to the similarly located signals in block A-B.

Signal S¹ is controlled by a line relay R¹, the operating circuit for this signal being 85 from a battery E¹, through wires 20, 177 and 21, contact 22 of relay R¹, wire 23, operating mechanism of signal S¹, wire 24, contact 25 of relay R¹, and wires 26, 27 and 28 to battery E¹. Signal S³ is similarly controlled 90 by a line relay R³, and the home arm H of signal S⁵ is similarly controlled by a line relay R⁵. The operating circuits for signals S⁷, S⁹, S⁸, S² and S⁴, and for the home arms of signals S¹⁰ and S⁶ will be readily 95 understood without further explanation.

The distant signal S¹¹ is controlled by a line relay Q¹¹, the circuit being from battery E¹⁰, through wires 29 and 30, contact 31 of relay Q¹¹, wire 32, operating mechanism of signal S¹¹, wire 33, contact 34 of relay Q¹¹, and wires 35, 36 and 37 to battery E¹⁰. The distant arm D of signal S⁵ is controlled by line relay R⁵ and by line relay Q⁵, 100

the circuit being from battery E^{12} , through wires 38, 39 and 40, contact 41 of relay Q^5 , wire 42, operating mechanism for the distant arm D, wires 43, and 44, contact 45 of relay R' , and wires 46, 47 and 48 to battery E^{12} . The controlling circuits for signals S^{14} and S^{12} , and for the distant arms D of signals S^{10} and S^6 will be understood from the foregoing without further explanation.

Line relay R' , which controls signal S' , is provided with a circuit which passes from battery E^8 , through wires 49, 50, 51, 52 and 53, contact 54 of track relay T^6 , wire 55, contact 56 of track relay T^5 , wire 57, contact 58 of track relay T^4 , wire 59, contact 60 of track relay T^3 , wires 61 and 62, contact 63 of track relay T^2 , wire 64, winding of relay R' , common wire O, and wires 65, 66, 67 and 68 to battery E^8 . It will be seen, therefore, that an eastbound train places signal S' at stop upon passing this signal, and that this signal remains in the stop position until such train passes point 10. Similarly, a westbound train passing point 10 places signal S' at stop and holds the signal in this position until the train passes the signal itself.

Line relay R^3 , which controls signal S^3 , is provided with a circuit which passes from battery E^{12} , through wires 69, 70, 71 and 72, contact 73 of track relay T^8 , wires 74 and 75, contact 76 of track relay T^7 , wire 77, contact 78 of track relay T^6 , wires 79 and 79^a, back contact 196 of a relay L^{16} , wire 80, contact 81 of track relay T^5 , wire 82, winding of relay R^3 , common wire O and wires 83, 47, and 48 to battery E^{12} . It will be seen, therefore, that an eastbound train passing signal S^3 places this signal at stop, and that the signal remains in the stop position until such train passes point 12. Similarly, a westbound train passing point 12 places signal S^3 at stop and holds the signal in this position until such train passes point 8 at which the signal is located.

The circuit for relay R^5 , which controls the home arm H of signal S^5 , is from battery E^{13} , through wires 84, 85, 86, 87 and 88, contact 89 of track relay T^{11} , wire 90, contact 91 of track relay T^{10} , wire 92, contact 93 of track relay T^9 , wire 94, winding of relay R^5 , common wire O and wires 95, 96 and 97 to battery E^{13} . It will be seen, therefore, that an eastbound train places signal S^5 at stop upon passing such signal, and that this signal remains in the stop position until the train passes point 15. Similarly, a westbound train places signal S^5 in stop position upon passing point 15, and holds the signal at stop until it passes the signal itself.

The controlling circuit for each of the remaining line relays R will be understood from the foregoing without further explanation.

The circuit for relay Q^5 , which controls the distant arm D of signal S^5 , passes from battery E^{13} , through wires 85, 86, 87, 103, and 104, contact 105 operated by signal S^7 , wire 106, contact 107 operated by the home arm H of signal S^5 , wire 108, winding of relay Q^5 , wires 109, 47 and 83, common wire O, and wires 95, 96 and 97 to battery E^{13} . It will be seen, therefore, that when an eastbound train passes along the track, distant arm D of signal S^5 will remain in the caution position until signal S^7 returns to the proceed position, that is, until such train passes point 19.

The circuit for line relay Q^{11} , which controls the distant signal S^{11} , is from battery E^{12} , through wires 38, 69, 70, 71 and 72, contact 73 of track relay T^8 , wires 74 and 98, contact 99 operated by the home arm H of signal S^5 , wire 100, contact 101 operated by the distant arm D of signal S^5 , wire 102, winding of relay Q^{11} , common wire O and wires 83, 47 and 48 to battery E^{12} . It will be seen, therefore, that an eastbound train passing signal S^{11} places this signal in the caution position, and that the signal remains in such position until signal S^5 returns to the full proceed position, that is, until the train passes point 19.

The control of the relays Q which govern signals S^{14} , S^{12} and of the distant arms D of signals S^{10} and S^6 will be understood from the foregoing without further explanation.

Located in the trackway adjacent each signal is a trackway device designated by the reference character K, with an exponent corresponding to that of the adjacent signal. As here shown (see Fig. 4) each of these devices comprises a permanent magnet P provided with a neutralizing winding 123. It is understood that each train is provided with governing means arranged to co-operate with these trackway devices in such manner that when the train passes over the device a stop indication is given aboard the train if the winding 123 is de-energized, but a proceed indication is given aboard the train if this winding is energized. Although as here shown, these trackway devices are in the form of magnets, it is understood that any other device arranged to co-operate with the train governing means in the manner specified, may be substituted for the devices shown herein. The devices K will herein-after be termed magnets to simplify the discussion.

Two additional magnets K^{15} and K^{16} are provided for the block A-B, which magnets are located respectively at maximum braking distance in the rear of signals S^3 and S^4 . Two similar additional magnets K^{17} and K^{18} are provided for the block to the east of siding B.

Each magnet K is controlled in such manner that it is adapted for co-operation with

trains moving in both directions, and in order to accomplish this with the simplest arrangement of train carried apparatus each magnet is located midway between the two track rails 2 and 2^a. That is, with this arrangement of the magnets each train need be equipped with only one receiving device, instead of with two such devices as would be required if the magnets were not located 10 midway between the rails as described.

Each magnet K, with the exception of K¹⁵, K¹⁶, K¹⁷ and K¹⁸, is located at the junction of two adjacent track sections. For 15 reasons which will appear hereinafter, the insulated joints 3 at each such magnet location are staggered as shown in the drawings, the magnet being located between the two joints.

Each magnet K is provided with a controlling relay which is designated by the reference character J with the same exponent as that of the corresponding magnet. Considering magnet K', for example, the circuit for this magnet is from battery E², 25 through wire 143, contact 144 of relay J', wire 145, winding on magnet K', and wire 146 to battery E². The controlling circuit for each magnet is similar to the circuit just traced for magnet K'.

30 Relay J', which controls the magnet K', is provided with two circuits, one of which is as follows: from battery E', through wires 20 and 110, contact 111 of line relay R', wire 112, back point of contact 113 of track 35 relay T', wire 114, front point of contact 115 of track relay T², wires 116 and 117, winding of relay J' and wires 118 and 28 to battery E'. This circuit is closed when an eastbound train occupies track section 4-5, 40 provided that line relay R' is energized; that is, provided that the track is unoccupied from point 5 to point 10. After the eastbound train passes point 5, this circuit is opened by line relay R', and, consequently, 45 the magnet K' cannot again be energized until the train has passed point 10. This circuit I will call the eastbound circuit for relay J'.

The other circuit for relay J' is from battery E', through wire 119, contact 120 of line relay Q⁶, wire 121, back point of contact 115 of track relay T², wire 114, front point of contact 113 of track relay T', wires 122 and 117, winding of relay J' and wires 118 and 28 to battery E'. This circuit is closed 55 when a westbound train occupies track section 5-6, provided that at such time relay Q⁶ is energized, and so I will term it the westbound circuit for relay J'.

60 The control of relay J⁷ which governs magnet K⁷ is similar to the control of relay J', and hence detailed explanation is not required.

65 Relay J¹¹, which governs the magnet K¹¹, is provided with two circuits. The east-

bound circuit is from battery E¹⁰, through wires 29 and 124, back contact 125 of track relay T⁷, wire 126, front point of contact 127 of relay Q¹¹, wire 128, winding of relay J¹¹, and wires 129 and 37 to battery E¹⁰. 70 This circuit is closed when an eastbound train occupies track section 10-11, provided that relay Q¹¹ is closed; that is, provided that the track is unoccupied between point 11 and point 19. The westbound circuit 75 for relay J¹¹ is from battery E⁶, through wires 130, 130^a, 131, 132 and 133, contact 134 of track relay T⁴, wire 135, contact 136 of track relay T⁶, wires 137 and 138, contact 139 of track relay T⁶, wire 140, contact 141 of track relay T⁷, wire 142^a and 142, back point of contact 127 of relay Q¹¹, wire 128, winding of relay J¹¹, wires 129, 36 and 36^a, common wire O, and wires 197, 198, 154 and 155 to battery E⁶. It will be seen that 80 this circuit is closed when a westbound train occupies track section 11-12, provided that the track between points 11 and 7 is unoccupied.

The control of relays J¹² and J¹⁴ is similar 85 to the control of relay J¹¹, and hence no further explanation is required.

The intermediate magnets K³ and K⁴, as well as the additional magnets K¹⁵ and K¹⁶, are controlled by two stick relays L¹⁵ 95 and L¹⁶.

Relay L¹⁵ is provided with a pick-up circuit which passes from battery E⁶, through wires 130, 130^a, 131, 132 and 147, contact 148 operated by signal S³, wire 149, back contact 100 150 of track relay T⁴, wires 151 and 152, winding of relay L¹⁵, and wires 153, 154 and 155 to battery E⁶. This circuit is closed when a train moving toward the east enters track section 7-8 provided that signal S³ 105 indicates proceed. The stick or holding circuit for relay L¹⁵ is from battery E⁶, through wires 130, 130^a and 156, back point of contact 157 of line relay R³, wire 158, contact 159 of relay L¹⁵, wires 160 and 152, winding 110 of relay L¹⁵, and wires 153, 154 and 155 to battery E⁶. This circuit becomes closed when an eastbound train enters section 8-9, provided that relay L¹⁵ was previously energized, and it then remains closed as long 115 as line relay R³ remains open. It will be seen from the foregoing that relay L¹⁵ is closed under certain conditions during an eastbound movement along the track as the train approaches magnet K³, but that this 120 relay is never closed during a westbound movement.

Relay L¹⁶ is controlled in a manner similar to relay L¹⁵. That is, the pick-up circuit for relay L¹⁶ includes back contact 161 of 125 track relay T⁶ and contact 162 operated by signal S⁴. The stick or holding circuit for this relay is controlled by the back point of contact 163 of line relay R⁴. It follows that when a westbound train enters section 130

- 9—10 relay L^{16} becomes energized, provided that signal S^4 is in the proceed position, and that relay L^{16} then continues to be energized until line relay R^4 closes due to such train 5 passing point 5. Relay L^{16} never becomes energized, however, during the passage of an eastbound train along the track.
- Relay J^{15} , which controls magnet K^{15} , is provided with two circuits, one of which is 10 closed only when relay L^{15} is closed and which passes from battery E^8 , through wires 49, 50, 51, 52 and 53, contact 54 of track relay T^6 , wire 55, contact 56 of track relay T^5 , wires 57 and 164, front point of 15 contact 165 of relay L^{15} , wire 166, winding of relay J^{15} , wire 167, common wire O , and wires 65, 66, 67 and 68 to battery E^8 . This circuit, which may be termed the eastbound circuit for relay J^{15} , is closed when an eastbound train enters section 7—8, provided that 20 relay L^{15} is energized, that is, provided that the track is unoccupied from point 8 to point 12. The other circuit for relay J^{15} , which may be termed "the westbound circuit", is from battery E^8 , through wires 49 and 168, contact 169 of relay L^{16} , wire 170, back point of contact 165 of relay L^{15} , wire 166, winding of relay J^{15} , wire 167, common wire O , and wires 65, 66, 67 and 68 25 to battery E^8 . When a westbound train occupies section 7—8 this circuit is closed, provided that relay L^{16} was energized when the train passed signal S^4 , that is, provided that the track is unoccupied from point 7 to 30 point 5.
- The control of relay J^{16} is similar to the control of relay J^{15} . That is, relay J^{16} is provided with a westbound circuit which includes the front point of contact 171 of relay L^{16} , and also track relay contacts 136 and 40 134. Relay J^{16} is also provided with an eastbound circuit which includes the back point of contact 171 of relay L^{16} and front point of contact 172 of relay L^{15} .
- 45 Relay J^3 , which controls magnet K^3 , is provided with two circuits which may be termed the "Eastbound" and the "Westbound" circuits. The eastbound circuit is from battery E^6 , through wires 130, 130^a and 156, front point of contact 157 of relay R^3 , wire 173, front point of contact 174 of relay L^{15} , wire 175, winding of relay J^3 and wires 176 and 155 to battery E^6 . This circuit is closed when an eastbound train enters track 50 section 8—9, provided that at such time relay R^3 is closed, that is, provided that the track is unoccupied from point 8 to point 12. The westbound circuit for relay J^3 is from battery E' , through wires 20, 177, 178, 179 and 180, contact 181 of track relay T^2 , wires 182 and 183, contact 184 of track relay T^3 , wire 185, contact 186, of track relay T^4 , wires 187 and 188, back contact 189 of relay R^3 , wire 190, back point of contact 174 of relay L^{15} , wire 175, winding of relay J^3 , wires 176, 55 154, 198, 197, common wire O , and wires 27^a, 27 and 28 to battery E' . It will be observed that this circuit is closed while a westbound train occupies track section 8—9, provided that the track is unoccupied from point 8 to point 5.
- 154, 198, 197, common wire O , and wires 27^a, 27 and 28 to battery E' . It will be observed that this circuit is closed while a westbound train occupies track section 8—9, provided that the track is unoccupied from point 8 to point 5.
- Relay J^4 , which controls the magnet K^4 is similarly provided with a westbound and an eastbound circuit. The westbound circuit for this relay is controlled by front 75 point of contact 163 of line relay R^4 and the front point of contact 191 of relay L^{16} . The eastbound circuit for this relay is controlled by contact 73 of track relay T^8 , contact 76 of track relay T^7 , contact 78 of track relay T^6 , back contact 192 of line relay R^4 , and back point of contact 191 of relay L^{16} . This circuit is closed when an eastbound train occupies track section 8—9, provided that the track is unoccupied between points 9 and 12. 80
- The control of relays J^{17} , J^{18} , J^9 and J^8 for the block to the east of siding B is the same as the control of the corresponding relays for block A—B.
- The operation of the apparatus during the 90 passage of an eastbound train along the track is as follows:
- Prior to the time that such train has reached point 4, it has opened relays R^6 and Q^6 , thereby causing signal S^6 to move to the 95 stop position, and this movement of signal S^6 opens the circuit for relay Q^{12} , so that signal S^{12} has assumed the caution aspect. The opening of relay Q^6 has opened at contact 120 the westbound circuit for relay J' , 100 so that magnet K' cannot be energized by a westbound train. Similarly, the opening of relay Q^{12} has opened at the front point of contact 193 the westbound circuit for relay J^{12} , and has closed the eastbound circuit for 105 this relay at the back point of the same contact, so that magnet K^{12} becomes energized.
- As the eastbound train enters section 4—5 it opens track relay T' , thereby closing at contact 113 the eastbound circuit for relay J' so that magnet K' becomes energized. As 110 the train enters track section 5—6, it opens track relay T^2 , thereby opening at contact 181 the circuit for line relay R^4 , so that signal S^4 moves to the stop position. The opening of relay R^4 also closes at back contact 192 the eastbound circuit for relay J^4 , but it opens at the front point of contact 163 the westbound circuit for relay J^4 , so that a westbound train cannot cause magnet K^4 to 115 become energized. The opening of contact 63 of track relay T^2 breaks the circuit of line relay R^4 , so that signal S' moves to the stop position. Magnet K' is energized when the forward end of the train passes over this magnet, so that a proceed indication is received aboard the train at this magnet, assuming of course, that the track is unoccupied between point 5 and point 10. When 120 the rear end of the train passes out of track 125 130

section 4—5, the closing of track relay T^6 allows relay R^6 to close, so that home arm H of signal S^6 moves to the proceed position. Relay Q^6 then closes, so that the distant arm D of this signal also moves to the proceed position, so that signal S^6 then indicates proceed.

Relay Q^{12} is opened while the train occupies track section 5—6, thereby closing at contact 193 the eastbound circuit for relay J^{12} , so that if the track is unoccupied between point 6 and point 10 this relay closes, and the train receives a proceed indication at magnet K^{12} .

As the train enters track section 6—7, it opens track relay T^3 , but this causes no change in the condition of the apparatus, except that it prevents a following eastbound train from closing the eastbound circuit for relay J^{12} . As the rear end of the train passes out of track section 5—6, the closing of track relay T^2 permits relay Q^{12} to close, so that signal S^{12} returns to the proceed position.

As the train enters track section 7—8, it opens track relay T^4 , thereby closing at contact 150 the pick-up circuit for relay L^{15} , assuming of course, that signal S^3 is in the proceed position. The eastbound circuit for relay J^{15} is closed, so that a proceed indication is received aboard the train as the train passes magnet K^{15} . The opening of contact 134 of track relay T^4 opens the circuit for relay R^2 , so that signal S^2 moves to the stop position and the consequent opening of the circuit controller operated by signal S^2 opens the circuit for relay Q^{10} so that the distant blade D of signal S^{10} moves to the caution position. This opens the circuit for relay Q^{14} so that signal S^{14} moves to the caution position. The opening of line relay R^2 also opens at contact 194 the westbound circuit for relay J^2 , so that a westbound train approaching signal S^2 cannot cause the magnet K^2 to become energized.

As the train enters track section 8—9, it receives a proceed indication at magnet K^3 , because the eastbound circuit for relay J^3 is closed at contacts 174 and 157. The opening of track relay T^5 , however, opens line relay R^3 , so that signal S^3 moves to the stop position and magnet K^3 becomes de-energized. The back point of contact 157 of relay R^3 closes the stick circuit for relay L^{15} , so that this relay then remains energized, even though its pick-up circuit immediately becomes opened at contact 148. Contact 56 of relay T^5 opens the eastbound circuit for relay J^{15} , so that magnet K^{15} then becomes de-energized.

While the eastbound train is in section 8—9, the eastbound circuit for relay J^4 is closed at contact 192 of relay R^4 , so that the train receives a proceed indication at magnet K^4 , provided, of course, that the track is unoccupied between points 9 and 12.

As the train enters section 9—10, it opens track relay T^6 , but this causes no change in the condition of the apparatus. The eastbound circuit for relay J^{16} is now closed at contacts 171 and 172, so that as the train passes over magnet K^{16} it receives a proceed indication.

As the train enters section 10—11, the opening of track relay T^7 closes at contact 125 the eastbound circuit for relay J^{11} , so that the train will receive a proceed indication upon passing over magnet K^{11} . When the rear end of the train passes out of section 9—10, the closing of track relay T^6 permits relay R' to close, so that signal S' returns to the proceed position, and a following eastbound train is enabled to cause magnet K' to be energized. Such a following train would also receive proceed indication at magnets K^{12} and K^{15} but it would be unable to energize relay J^3 , because the eastbound circuit for this relay is open at the front point of contact 157 of relay R^3 , and, consequently, the train would receive a stop indication at magnet K^3 .

When the first train enters track section 11—12 the opening of track relay T^8 opens at contact 73^a the circuit for relay R^{16} , so that the home blade H of signal S^{10} moves to the stop position. The operation of track relay T^8 closes at contact 195 the eastbound circuit for relay J^2 , so that when a train passes over magnet K^2 it will receive a proceed indication.

As the train passes into track section 12—13 the opening of track relay T^9 opens at contact 93 the circuit for line relay R^5 , so that signal S^5 moves to the stop position. When the rear end of the train passes out of track section 11—12 the closing of relay T^8 closes at contact 73 the circuit for line relay R^3 so that signal S^3 returns to the proceed position and stick relay L^{15} opens. Relay R^4 then closes, so that signal S^4 returns to the proceed position. A following train can then energize relay J^3 and so will receive a proceed indication at magnet K^3 . Similarly, the following train is enabled to energize relay J^4 and so will receive a proceed indication at magnet K^4 . The same thing is true as to magnet K^{16} , but the following train cannot energize relay J^{11} , because the circuit for this relay is open at contact 127 of relay Q^{11} , and so such following train will receive a stop indication at magnet K^{11} .

When the first train enters track section 13—14, the opening of track relay T^{10} closes the eastbound circuit for relay J^7 , so that the train will receive a proceed indication at magnet K^7 . As the train enters section 14—15, it will place signal S' in the stop position and permit signal S^{10} to return to the proceed position. As the train enters section 15—16, it will permit signal

- S¹⁴ to return to the proceed position and will also permit home arm H of signal S⁵ to return to the inclined position due to the fact that line relay R⁵ becomes energized. 5 The operation of the apparatus during the progress of the train through the remainder of the stretch of track shown in the drawings will be understood without further explanation. It should be noted that the dis- 10 tant arm D of signal S⁵ will not return to the inclined or proceed position until signal S⁷ returns to the proceed position, that is, until the rear of the train passes out of track section 18-19.
- 15 The operation of the apparatus during the movement of a train along the track from east to west, will be understood from the foregoing without further explanation. As hereinbefore pointed out, each magnet 20 K, except K¹⁵, K¹⁶, K¹⁷ and K¹⁸, is located between the staggered insulating joints 3 which separate the adjoining track sections. The object of this is to prevent a train from de-energizing the magnet until the train- 25 carried receiving device, which will usually be behind the front axle of the train, has passed the magnet.
- In certain of the claims I have used the expression eastbound signal, westbound signal, eastbound device and the like, but it is understood that these expressions are for ready reference to the drawing only, and are to be construed as covering the signals and track devices on a single track extend- 30 ing in any two directions.
- Although I have herein shown and de- 35 scribed only one form and arrangement of trackway apparatus embodying my invention, it is understood that various changes and modifications may be made therein within the scope of the appended claims without departing from the spirit and scope of my invention.
- Having thus described my invention, what 40 I claim is:
1. In combination, a stretch of single track over which traffic moves in both directions, said stretch being divided into blocks, two end signals for each block for govern- 45 ing traffic into said block, two intermediate signals for each block located in advance of the two end signals respectively, means for controlling each end signal up to a point beyond the opposing intermediate signal, 50 means for controlling each intermediate signal up to the end of the block towards which such signal governs traffic, trackway devices each arranged to give a proceed or a stop indication aboard a train according as the device is energized or de- 55 energized, one such device being located adjacent each signal and two additional devices being located in the rear of the two intermediate signals respectively, means con- 60 trolled by a train entering the block for 65 energizing the trackway device adjacent the corresponding end signal if the block is unoccupied up to the point to which such signal is controlled, and for thereafter preventing such device from being energized 70 until the train has passed such point, means controlled by a train passing through said block for energizing the first additional trackway device if the block is unoccupied between the first intermediate signal and 75 the end of the block which the train is approaching and for preventing the energization of such device until after the train has passed the second intermediate signal, means controlled by a train passing through said 80 block for energizing the trackway device adjacent the first intermediate signal if the block is unoccupied between such signal and the end of the block which the train is approaching and for subsequently preventing 85 such device from being energized while the train is between said two points, means controlled by a train passing through said stretch and approaching the second intermediate signal for energizing the trackway de- 90 vice adjacent such signal if the block is unoccupied between such signal and the end of the block which the train is approaching and for subsequently preventing the energization of such device while the train is 95 between such two points, means controlled by a train passing through said block and approaching the second additional trackway device for energizing such device, and means controlled by a train approaching the end 100 signal at the exit end of the block for energizing the trackway device adjacent such signal if the track in advance of such signal is unoccupied up to a predetermined point and for subsequently preventing the 105 energization of such device while the train occupies any part of the track up to said predetermined point.
  2. In the combination, a stretch of railway track over which traffic moves in both directions, two signals at one location for governing traffic in opposite directions, a trackway device at said location arranged when energized to give a proceed indication aboard a train, and means for controlling said device in accordance with the indication given by one of said signals or the other according to the direction of movement of a train passing the device.
  3. In combination, a stretch of railway track over which traffic moves in both directions, two signals at one location for governing traffic in opposite directions, a trackway device at said location arranged when energized to give a proceed indication aboard a train, two circuits for controlling the energization of said device and governed in accordance with the indications given by said two signals respectively, and means for selecting one or the other of said circuits ac- 120 125 130

- cording to the direction of movement of a train passing said device.
4. In combination, a stretch of railway track over which traffic moves in both directions, two signals at one location for governing traffic in opposite directions, track circuits for said stretch for controlling said signals, a trackway device at said location arranged when energized to give a proceed indication aboard a train, and means controlled by a train approaching said location for governing said device in accordance with the indication given by the signal corresponding to the direction in which the train is moving.
5. In combination, a stretch of railway track over which traffic moves in both directions, two signals at one location for governing traffic in opposite directions, track circuits for said stretch for controlling said signals, a trackway device at said location arranged when energized to give a proceed indication aboard a train, two circuits for causing energization of said device and controlled in accordance with the indications given by said two signals respectively, and means controlled by a train approaching said location for placing said device under the control of the circuit corresponding to the direction in which the train is moving.
6. In combination, a stretch of railway track over which traffic moves in both directions, two signals at one location for governing traffic in opposite directions, track circuits for said stretch for controlling said signals, a trackway device at said location arranged when energized to give a proceed indication aboard a train, a partial circuit for governing the energization of said device and closed when one of said signals indicates proceed, means for completing said circuit when a train moving in the direction in which such signal governs traffic approaches said device, a second partial circuit for governing the energization of said device and closed when the other signal indicates proceed, and means for completing said second circuit when a train moving in the opposite direction approaches said device.
7. In combination, two adjoining sections of railway track over which traffic moves in both directions, a trackway device located at the junction of said sections and adapted when energized to give a proceed indication aboard a train, and means controlled by trains for energizing said device when either section is occupied and the other section is unoccupied.
8. In combination, two adjoining sections of railway track over which traffic moves in both directions, a trackway device located at the junction of said sections, and means for placing said device in non-retarding condi-
- tion when either of said sections is unoccupied and a train is in the other section approaching the device.
9. In combination, two adjoining sections of railway track over which traffic moves in both directions, each section having a plurality of track circuits, a trackway device located at the junction of said sections, and means for placing said device in non-retarding condition when either section is unoccupied and a train occupies that track circuit of the other section lying next to the device.
10. In combination, two adjoining sections of railway track over which traffic moves in both directions, a trackway device located at the junction of said sections, and means for placing said device in non-retarding condition when either of said sections is occupied and the other is unoccupied.
11. In combination, a stretch of railway track over which traffic moves in both directions, two signals at one location for governing traffic in opposite directions, a trackway device at said location arranged when energized to give a proceed indication aboard a train, two signal relays for controlling said two signals respectively, means for controlling each relay by traffic conditions in advance of said location in the direction in which the corresponding signal governs traffic, and means controlled by a train approaching said device from one direction or the other for causing the device to be energized if the relay which controls the signal governing traffic in the direction in which the train is moving is closed.
12. In combination, a stretch of railway track over which traffic moves in both directions, an eastbound signal and a westbound signal at one location for governing traffic in opposite directions along said stretch, track circuits for the stretch, two signal relays for controlling said two signals respectively and each controlled by a plurality of track circuits in advance of said location in the direction in which the corresponding signal governs traffic, a trackway device at said location arranged when energized to give a proceed indication aboard a train, a circuit for controlling the energization of said device when the eastbound signal relay is closed and an eastbound train occupies the first track circuit to the west of said location, and a second circuit for controlling the energization of said device when the westbound signal relay is closed and a westbound train occupies the first track circuit to the east of said location.
13. In combination, a track circuited stretch of railway track over which traffic moves in both directions, an eastbound signal, a trackway device located adjacent said signal and arranged when energized to give a proceed indication aboard a train, a signal

- relay for said signal controlled by a plurality of track circuits to the east of said signal, a stick relay, means controlled by an eastbound train for closing said stick relay as the train approaches the signal and keeping it closed until the train leaves the last track circuit controlling said signal, an eastbound circuit for said trackway device closed while said stick relay and said signal relay are both closed, and a westbound circuit for said device closed while said signal relay is open if each of a plurality of track circuits lying to the west of the device is unoccupied. 14. In combination, a track circuited stretch of railway track over which traffic moves in both directions, an eastbound signal, a trackway device located adjacent said signal and normally in condition to retard a train, a signal relay for said signal controlled by a plurality of track circuits to the east of the signal, a stick relay, means controlled by an eastbound train for closing said stick relay as the train approaches the signal and keeping it closed until the train leaves the last of said track circuits to the east of the signal, means for placing said device in non-retarding condition when said signal relay and said stick relay are both closed and other means for placing said device in non-retarding condition when said signal relay is open if each of a plurality of track circuits to the west of the device is unoccupied. 15. In combination, a stretch of railway track over which traffic moves in both directions, an eastbound signal and a westbound signal, a trackway device located in the rear of the eastbound signal and normally in condition to retard a train, means controlled by an eastbound train approaching said device for placing the device in non-retarding condition if the eastbound signal indicates proceed and for keeping the device in such condition until it has been passed by the train, and means controlled by a westbound train approaching said westbound signal for placing said device in non-retarding condition and keeping it in such condition until it has been passed by the train. 16. In combination, a stretch of railway track over which traffic moves in both directions, an eastbound signal and a westbound signal governing traffic along said track, a trackway device located in the rear of the eastbound signal, an eastbound stick relay and a westbound stick relay, means controlled by an eastbound train approaching said device for closing said eastbound stick relay if the eastbound signal indicates proceed and for keeping the eastbound stick relay closed until the eastbound signal returns to the proceed position, means controlled by a westbound train approaching the westbound signal for closing the westbound stick relay provided the last-mentioned signal indicates proceed and for keeping such relay energized until the westbound train subsequently releases the westbound signal from the stop position, and means for placing said trackway device in non-retarding condition when either of said stick relays is closed. 17. In combination, a stretch of railway track over which traffic moves in both directions, an eastbound signal and a westbound signal governing traffic along said track, an eastbound trackway device located in the rear of the eastbound signal and a westbound trackway device located in the rear of the westbound signal, each device being normally in condition to retard a train, means controlled by an eastbound train approaching the eastbound device for placing said device and also the westbound device in non-retarding condition if the eastbound signal indicates proceed and for keeping each of said devices in such condition until they have been passed by the train, and means controlled by a westbound train approaching the westbound device for placing both of said devices in non-retarding condition if the westbound signal indicates proceed and keeping each device in such condition until it has been passed by the train. 18. In combination, a stretch of railway track over which traffic moves in both directions, an eastbound signal and a westbound signal for governing traffic along said track, an eastbound trackway device located in the rear of the eastbound signal and a westbound trackway device located in the rear of the westbound signal, each device being normally in condition to retard a train, an eastbound stick relay and a westbound stick relay, means controlled by an eastbound train approaching the eastbound device for closing the eastbound stick relay if the eastbound signal indicates proceed and for keeping such relay closed as long as such signal indicates stop, means controlled by a westbound train approaching the westbound device for closing the westbound stick relay if the westbound signal indicates proceed and for keeping such relay closed as long as the westbound signal indicates stop, and means for placing each trackway device in non-retarding condition when one of said stick relays is closed and the other open. 19. In combination, a stretch of railway track including two sections separated by staggered insulated rail joints, a trackway device located between said joints and adapted when energized to give a proceed indication aboard a train, and means controlled by a train in either section approach-

ing said device for energizing the device if the track is unoccupied for a given distance beyond said device.

20. In combination, a stretch of railway track including two sections separated by staggered insulated rail joints, a trackway device located between said joints and adapted when energized to give a proceed indication aboard a train, and means controlled by a train moving in either direction along the track for energizing said device while the train occupies the section in the rear of the device if the track is unoccupied for a given distance beyond the device, and for de-energizing the device when the train enters the section in advance of the device.

21. In combination, a stretch of railway track including two sections separated by staggered insulated rail joints, a trackway device located between said joints and adapted when energized to give a proceed indication aboard a train, a track circuit for each section including a track relay, and means controlled in part by said track relays for energizing said device when the relay for either section is open provided that the track is unoccupied for a given distance on the other side of the device.

22. In combination, a stretch of railway track including two sections separated by staggered insulated rail joints, a trackway device located between said joints and adapted when energized to give a proceed indication aboard a train, a track circuit for each section including a track relay, and means for energizing said device when

either relay is open and the other closed, but for preventing energization of the device when both relays are open.

40

23. In combination, a stretch of railway track including two sections separated by staggered insulated rail joints, a trackway device located between said joints and adapted when energized to give a proceed indication aboard a train, a track circuit for each section including a track relay, and means controlled by a train moving in either direction for de-energizing said device when the relay for the section in advance of the device is opened by the train.

50

24. In combination, a stretch of railway track including two sections separated by staggered insulated rail joints, a trackway device located between said joints and arranged for co-operation with trains moving in both directions, said device being normally in condition to retard a train, and means controlled by a train approaching said device from either direction for placing said device in non-retarding condition if the track is unoccupied for a given distance on the other side of the device.

55

25. In combination, a stretch of railway track including two sections separated by staggered insulated rail joints, a trackway device located between said joints and arranged for co-operation with trains moving in both directions, and means for controlling said device by traffic conditions in both of said sections.
